UNITED STATES PATENT OFFICE.

CARL EMIL FIEDLER, OF KLINGENTHAL, GERMANY.

ZITHER.

SPECIFICATION forming part of Letters Patent No. 692,773, dated February 4, 1902.

Application filed September 6, 1901. Serial No. 74,582. (No model.)

To all whom it may concern:

Be it known that I, CARL EMIL FIEDLER, a subject of the Emperor of Germany, residing at Klingenthal, Saxony, Germany, have invented certain new and useful Improvements in Zithers, of which the following is a specification.

This invention relates to zithers, and has for its object to provide improved means where-
10 by it is possible to very conveniently locate the strings in playing the instrument to pro-
duce a great volume of sound and to render the whole arrangement more effective.

With this object in view the invention con-
15 sists in the improved construction, arrange-
ment, and combination of parts hereinafter
fully described and afterward specifically
claimed.

The invention is illustrated in the accom-
20 panying drawings, in which—

Figure 1 is a longitudinal section. Figs. 2
and 3 are elevations of the right and left hand
faces, respectively, of a zither, while Fig. 4 is
a transverse section on the line xx , Fig. 3.

25 As illustrated in the drawings, the sound-
ing-board a' is provided with an aperture A,
on the bottom side of which a scale a is pro-
vided to correspond with the strings employed
and with the object of facilitating their loca-
30 tion when playing. Bridges d are provided
on each of the faces of the board a' and are

secured in position by the plates $b b'$ and are
capable of removal into various positions, as
indicated in dotted lines in Figs. 2 and 3. In
any position the bridges d are supported by 35
means of a transverse bridge c within the
sounding-board.

The strings are secured to pins $e e$ at the
base of the sounding-board and pass over the
bridges d on each side, as illustrated. The 40
pins e are covered by means of the base-piece
 h , which hinges on one side at g and is fas-
tened at the opposite side by any suitable
means.

Having thus described my invention, what 45
I claim as new, and desire to secure by Letters
Patent of the United States, is—

A zither comprising a hollow double-faced
sounding-board having an opening there-
through, strings passing across said opening 50
on each face of the board, a scale on the bot-
tom wall of the opening indicating the strings
by the corresponding notes, adjustable trans-
verse bridges on the outside of the board for
supporting the strings, and a bridge within 55
the board at right angles with and supporting
the outer bridges, substantially as described.

In testimony whereof I affix my signature.
CARL EMIL FIEDLER.

In presence of—

ERNST BUCKMANN,
FRANZ ED LUDWIG.
